UNITED STATES PATENT OFFICE.

EDGAR D. MISNER, OF DETROIT, MICHIGAN, ASSIGNOR, BY MESNE ASSIGNMENTS, TO LOVELL MANUFACTURING COMPANY, OF ERIE, PENNSYLVANIA, A CORPORATION OF PENNSYLVANIA.

WRINGER.

Application filed October 9, 1922. Serial No. 593,268.

The invention relates to wringers and refers particularly to wringers of that type in which the rolls are separated by a spring. One of the objects of the invention is to provide a simple compact mechanism in the wringer for moving the rolls into contact with each other and for separating the same. Further objects of the invention reside in the novel features of construction and combinations and arrangements of parts as more fully hereinafter set forth.

In the drawings:

Figure 1 is a side elevation partly in section of a wringer embodying my invention; 15 Figure 2 is a top plan view thereof with the handle omitted;

Figure 3 is an end view thereof.

Fig. 4 is an enlarged vertical section through the center of the adjusting screw, 20 the section being at right angles to the section of Fig. 1.

1 is the wringer frame comprising the complementary housing sections 2 and 3. 4 and 5 are respectively the upper and lower 25 operating rolls journaled in the bearings within the uprights of the frame, the upper roll being vertically movable toward and away from the lower roll. 6 is a resilient bowed member extending above the upper roll 4 and connected to its bearings by a slotted strap 6^a through which the spring extends to raise and lower the same. 7 is a post extending through the top rail of the frame and transversely of the bowed member, this post being operatively connected to the bowed member by means of the clip 8. 9 is a handle upon the post and above the wringer frame for facilitating in the manual inward longitudinal adjustment of 30 the post to press the upper roll into contact with the lower roll.

For holding the post in an inwardly adjusted position, I have provided the catch 10 in the form of hooks 11 which extend upwardly above the top rail of the frame and engage over the shoulder formed by the nut 12 upon the post 7 and also located above the top rail. The trip for releasing the catch comprises the releasing levers 13 extending above the top rail and pivoted thereto at 14, the hooks extending upwardly from these levers and preferably being integral therewith. The top rail is cut away at 15 for

the passage of the lever and hooks. The pivots for the levers are so located with respect to their hooks that the tendency of the post to move longitudinally outward does not effect the rotation of the levers to disengage the hooks from the nut, and furthermore, the levers have at their inner ends the intermeshing fingers 16.

For the purpose of moving the upper roll away from the lower roll upon releasing the post, I have provided the coil spring 17 inclosed within the top rail of the frame and surrounding the post, the upper end of this coil spring being secured to the sleeve 18 which is supported upon the cooperating inner ends of the levers 13 which embrace the post and the coil spring. The lower end of this coil spring is secured to the clip 8. For the purpose of varying the longitudinal inward movement of the post, its outer end is threaded and the nut 12 is rotatable about this outer end to vary its longitudinal position relative to the post.

19 is a drain board extending below the rolls 4 and 5, this drain board being laterally adjustable to either side of the rolls. For rigidly locking the drain board in its position of adjustment I have provided the strips 20 forming projections upon the inner sides of the depending flanges 21 of the frame, which strips engage in the elongated openings 22 located in the depending side flanges 23 of the drain board. These openings have the diverging downwardly and outwardly inclined upper edges 24 at the intersection of which depending lugs 25 are located, the arrangement being such that the strips when clamped against either upper edge has its ends adjacent to an end of the opening and the lug 25 so that lateral movement of the drain board is impossible.

For clamping the drain board in its adjusted positions, there is the rod 26 having the transversely bent end 27, this rod being journaled in the depending flanges 21 extending through the elongated openings 22. The rod has the cam portions 28 engageable with the lower edges of the elongated openings to force the drain board downwardly relative to the wringer frame and clamp the strips 20 against the upper edges of the openings. The cam portions of the rod 26 are formed merely by transversely cutting

away portions thereof a sufficient distance to permit of lateral adjustment of the drain board.

What I claim as my invention is:

- 5 1. In a wringer, the combination with a frame, of upper and lower rolls within said frame, a post extending transversely of said upper roll, said post being longitudinally movable inward to press said rolls into contact with each other, a coil spring surrounding said post, means conveying movement from said post to the upper roll and operatively connected to said spring and upper roll for resiliently moving the upper roll 10 away from said lower roll, a nut threaded upon said post, a releasing lever pivoted upon said frame and extending thereabove, and a catch actuated by said lever and engageable with said nut to hold said post 15 in an inwardly adjusted position.
- 20 2. In a wringer, the combination with a frame, of upper and lower rolls within said frame, a member extending above said upper roll and operatively connected to the same, a post extending through said frame and transversely of and operatively connected to said member, a nut threaded upon said post above said frame, a trip pivotally mounted upon said frame, a catch actuated 25

by said trip and adapted to engage said nut 30 when said post is in an inwardly adjusted position, a sleeve surrounding said post and supported independently of the post, and a coil spring surrounding said post and secured to said sleeve and a member extending above and operatively connected to said upper roll.

3. In a wringer, the combination with a frame, of upper and lower rolls within said frame, a resilient member extending above 40 said upper roll and operatively connected to the same, a post extending through said frame, and transversely of said resilient member, means for securing said post to said resilient member, a nut threaded upon said 45 post above said frame, releasing levers pivotally mounted upon said frame and having intermeshing inner ends, and extensions projecting over said nut and adapted to engage said nut when said post is in an inwardly adjusted position, a sleeve surrounding said post and supported upon the inner 50 ends of said releasing levers, and a coil spring surrounding said post and secured to said sleeve and clip.

In testimony whereof I affix my signature.

EDGAR D. MISNER.
